Primary Examiner—Bernard Ansher

[57] CLAIM

The ornamental design for a compressible cleft palate nurser, as shown and described.

DESCRIPTION

FIG. 1 is an assembled perspective view of the compressible cleft palate nurser showing my design;

FIG. 2 is a top plan view thereof;

FIG. 3 is a front elevational view thereof;

FIG. 4 is a left side elevational view thereof;

FIG. 5 is a bottom plan view thereof; and

FIG. 6 is an exploded perspective view thereof showing structure under the translucent cover.

The side opposite FIG. 3 is the same as that shown in FIG. 3 except that the container surface is plain.

The side opposite FIG. 4 is the mirror image of that shown in FIG. 4.

FIG. 1.

FIG. 2.

FIG. 3.

FIG. 4.

FIG. 6.

FIG. 5.
